UNITED STATES PATENT OFFICE.

EDWARD BOEHM, OF SAN ANTONIO, TEXAS.

BUILDING-BLOCK.

1,163,624.

Specification of Letters Patent. Patented May 16, 1916.

Application filed March 4, 1915. Serial No. 12,052.

To all whom it may concern:

Be it known that I, EDWARD BOEHM, a citizen of the United States, residing at San Antonio, in the county of Bexar and State of Texas, have invented certain new and useful Improvements in Building-Blocks, of which the following is a specification.

This invention relates to certain improvements in building blocks and the objects and nature of the invention will be readily understood by those skilled in the art in the light of the following description of the accompanying drawings illustrating what I now believe to be the preferred embodiments from among other formations and arrangements within the spirit and scope of my invention.

It is an object of the invention to provide a building block whereby a wall of maximum strength and minimum weight may be constructed.

A further object of the invention is to provide a building block of small cost to manufacture, light in weight and cheap to transport.

A still further object of the invention is to provide a building block in which there is the largest possible area of mortar bed with simplicity of structure and minimum weight.

A still further object of the invention is to provide a hollow building block capable of being interlocked in a course and when formed in courses the superimposed course interlocking with the course directly beneath it.

The invention consists in certain novel features in construction and in arrangements and formation as more fully and particularly pointed out hereinafter.

Referring to the accompanying drawings, Figure 1, is a perspective view of a block of my invention showing the top of the block. Fig. 2, is a perspective view of the block of my invention showing the bottom of the block. Fig. 3, is a vertical longitudinal section of a portion of a wall constructed of blocks of my invention.

In the drawings, I show a block having a top with lugs or ribs *a*, thereon. These lugs or ribs are so constructed as clearly shown in Fig. 3, of the drawings, as not to increase the thickness of the top wall. This construction whereby the top wall is of the same thickness throughout does away with any

possibilities of unequal expansion or contraction of the block during the processes of drying. The interior of the hollow block is divided into air spaces by vertical partitions or walls terminating in the same horizontal plane as the exterior surrounding walls of the block. The bottom of the block is open, and in use, the exterior surrounding walls and the interior dividing walls act as supports for the block. The exterior surrounding walls *d*, and the interior dividing walls *c*, which form air spaces or recesses *b*, in the hollow interior of the block, are formed to receive the ribs or lugs *a*, on the top of the block below it when the block is placed in position in constructing a wall. It will be seen that the lugs or ribs *a*, are formed on the top to correspond with the open bottom air spaces formed by the dividing walls in the hollow interior of the block.

Referring now particularly to Fig. 3, of the drawings, where a portion of a wall in process of construction with my blocks, is shown. The blocks are placed in courses with their open sides or bottom down and their ends abutting. A course is then built upon this first mentioned course by placing a series of the blocks with their ends abutting and their open sides down but in such a manner that the center of each block in the upper course is located directly above the abutting ends of the two blocks immediately beneath it. In this manner a wall is built up of a series of superimposed courses, the centers of the blocks in each course being directly above the joining ends of the blocks in the course immediately below it. It will be seen that due to the end walls and the transverse interior dividing wall that placing the blocks in a series of superimposed courses and in the manner described above, that the transverse dividing wall being placed directly above the abutting end walls of the blocks beneath it and the abutting end walls of the blocks in the upper course being placed directly above the transverse dividing walls of the blocks beneath them that a vertical weight supporting and strain sustaining wall will be formed by each of this series of vertically aligned end walls and interior dividing walls extending throughout the height and length of the wall constructed.

In building a wall of my blocks great rigidity and strength is obtained due to the fact that by my improved construction in a

hollow building block, a mortar bed of large area and peculiar construction, is provided. This mortar bed is formed by the top of the block and the ribs or lugs α , formed thereon and the coöperation of the open bottom having the air pockets formed by the dividing walls and side and end walls with this mortar bed will form a mortar joint of the greatest possible strength to resist strains and stresses applied to it from any angle, and will further provide a joint which is to all intents and purposes water proof.

As stated above, the blocks in constructing a wall, are placed with their open ends 15 or bottoms down and their ends abutting in a series of horizontal courses superimposed one above the other. Mortar is applied to the upper surface of a course, which is composed of a series of tops of the blocks and 20 their lugs, and then blocks with their open ends down are placed upon this mortar bed and its attendant mortar in the position explained hereinbefore.

Each block of the upper course with its 25 air spaces or recesses, formed by the side, end and interior dividing walls will fit down upon the lugs of the blocks beneath it and as these lugs are positioned so as to coöperate or enter these recesses, it will be 30 clearly seen that any possibility of lateral or longitudinal slipping of the block being positioned will be done away with and also any possibility of the block being moved out of alinement after positioning but before 35 hardening or setting of the interposed mortar will be likewise done away with. The first mentioned of these facts will most materially aid in the speed and accuracy with which a wall may be constructed, using 40 my block.

The surrounding wall of each air space or recess when placed upon the mortar bed of my blocks will surround each lug or rib on the mortar bed and lie between the side 45 and end walls of the lugs which walls forming in effect pockets between them which will be filled with mortar on the entry of the surrounding walls of the air spaces of the block above. The entering of the various 50 walls of the blocks above into these mortar filled pockets of the mortar bed will force the mortar up and around these walls so that upon hardening and setting of the mortar, the block above will be firmly and 55 rigidly anchored to the block beneath by its end, side and interior dividing walls, which walls will be completely embedded at their ends in a solid mass of mortar.

A wall may be constructed of my block in 60 any number of thicknesses or in any number of superimposed courses as the side and end walls may be used as mortar beds in addition to the most effective mortar beds provided by the tops of the blocks and their 65 lugs. The tops of these blocks are com-

pletely solid or closed as disclosed by the drawings and as described in the foregoing pages, but it would not deviate from the spirit and scope and essential features of my invention, to put openings or perforations at various positions on the mortar bed. These perforations if used, or applied, would act with the mortar to key the upper blocks upon the mortar beds. However, for all practical purposes, the solid and closed mortar bed has been found to give the greatest possible rigidity and strength, but I do not wish to limit my invention to such a bed.

My invention constituting peculiar hollow building block described in the foregoing pages is most aptly adapted for use in silo construction. The block may be made with any degree of curvature or in any other form without materially causing any complicated or expensive changes in its mode or method of manufacture. Take as an example, a silo constructed of my blocks and the following features will be brought out tending to show its peculiar adaptation to this class of building. Silos are subjected to an unusual and very strong radial tension from the inside tending to bulge and force outwardly the silo walls due to the fact that grain, fodder and other compact and heavy materials are stored in its interior. My blocks with their coöperating lugs and air spaces or recesses and with their great and effective mortar beds overcome this radial stress. It is readily seen in view of the foregoing description, that this tension or stress is completely taken up and overcome by the ends of the side, end and dividing walls of the blocks in contact with the ribs or lugs on the mortar bed formed on the block directly beneath them. Further, due to the vertically extending weight supporting and stress bearing walls formed by the alined end walls and dividing walls the blocks are materially aided in overcoming this internal radial stress.

The blocks of my invention are cheaply manufactured, simple in construction, and of the smallest possible weight from which the best results of strength and rigidity can be obtained. Due to their exceeding lightness, they are extremely cheap to transport as well as to handle in loading and unloading.

It is evident that various changes, variations and modifications might be resorted to in the forms, constructions and arrangements described without departing from the spirit and scope of my invention and hence I do not wish to limit my invention to the exact disclosure hereof.

What I claim is:

A hollow building block open on its under side, interior dividing walls forming air

- spaces therein, said interior walls and the end, side and top walls of said block of equal thickness throughout, a portion of said top above each of said air spaces 5 pressed outwardly to form a rib of approximately the same outline as the air space below and of a much smaller area than said space, said ribs equal in thickness to the walls and top of said block and said ribs 10 forming mortar grooves adapted to receive the depending walls of a superposed block, said walls occupying a small area of the
- mortar grooves formed by said ribs whereby the mortar placed in said grooves is forced a distance up and around said walls 15 locking them firmly to the top of the lower block, substantially as described.

In testimony whereof I affix my signature in presence of two witnesses.

EDWARD BOEHM.
